UNITED STATES PATENT OFFICE.

CHARLES MORGAN, OF FREEPORT, ILLINOIS, ASSIGNOR TO ARCADE MANUFACTURING COMPANY, OF FREEPORT, ILLINOIS, A CORPORATION OF ILLINOIS.

DESIGN FOR A FRAME FOR LEMON-SQUEEZERS.

47,932.

Specification for Design.

Patented Oct. 5, 1915.

Application filed May 21, 1914. Serial No. 840,134. Term of patent 7 years.

To all whom it may concern:

Be it known that I, CHARLES MORGAN, a citizen of the United States, residing at Freeport, in the county of Stephenson and State of Illinois, have invented a new, original, and ornamental Design for a Frame for Lemon-Squeezers, of which the following is a specification, reference being had to the accompanying drawing, forming part thereof.

The drawing illustrates my new design by

means of a side elevation of a frame for a lemon squeezer showing the same in upright operative position such as it occupies when in actual use.

I claim:

The ornamental design for a frame for a lemon squeezer, as shown.

CHARLES MORGAN.
